UNITED STATES PATENT OFFICE.

CHARLES WAID ROUSH, OF GRAND ISLAND, NEBRASKA.

WIRE-FASTENER.

No. 818,977.

Specification of Letters Patent.

Patented April 24, 1906.

Application filed September 19, 1905. Serial No. 279,186.

To all whom it may concern:

Be it known that I, CHARLES WAID ROUSH, a citizen of the United States, residing at Grand Island, in the county of Hall and State of Nebraska, have invented a new and useful Wire-Fastener, of which the following is a specification.

This invention relates to wire-fasteners, and has for an object to provide a device of the class embodying new and improved features of convenience, utility, and efficiency.

A further object of the invention is to provide a device for attachment to a post and embodying a plurality of spaced wire-receiving slots and a keeper to close the outer ends of the slots and retain the wire in such of them as found desirable, said keeper to extend to the ground or into the ground to any depth desired.

20 A further object of the invention is to provide a plate for attachment to a post and having spaced tongues at one side bent outwardly at right angles to the plate and forming a plurality of slots spaced vertically of 25 and disposed obliquely to the post. The outer ends of the tongues are curled to form alined openings at their outer ends, and a wire or rod is inserted through the several openings, thus closing the outer ends of the slots 30 and retaining such wires as may be therein.

With these and other objects in view the present invention consists in the combination and arrangement of parts, as will be herein-after fully described, shown in the accompanying drawings, and particularly pointed out in the appended claims, it being understood that changes in the form, proportion, size, and minor details may be made without departing from the spirit or sacrificing any 40 of the advantages of this invention.

In the drawings, Figure 1 is a perspective view of the improved wire-fastener applied to a post. Fig. 2 is a fragmentary view, in side elevation, of the tongues, slots, and keepers. Fig. 3 is a transverse sectional view of a post with the improved fastener applied.

Like characters of reference indicate corresponding parts in all of the figures of the drawings.

50 The improved wire-fastener forming the subject-matter of this application may be made in any size, length, and proportion and from any approved material and may be used for any purpose where it is desirable to attach a plurality of wires or the like to any 55 stationary object, but is especially and pecul-

iarly adapted to securing fence-wires, as 10, upon a post, as 11.

In its preferred form the invention comprises a plate 12, of sheet metal or other material and provided with holes for attachment to the post, as by the nails or screw 13. At one edge a plurality of tongues 14 are formed and bent with their planes at any desired angle to the plane of the plate and with their upper and lower edges inclined upwardly from the plate, defining obliquely-disposed slots 15. The outer ends of the tongues are rolled or curled, as at 16, to form alined openings and with the extremities of the tongues extending vertically above the top edge of the tongue, as at 17, and whereby the slots are contracted or constricted at their open outer ends. Through the several alined openings is inserted a wire or rod 18, having a ring or other means of handling, as 19, at the upper end and comprising a keeper to close the outer ends of the several slots.

20 In use the plate is secured to the face of the post 11 and the wires 10 placed in such slots as will provide the desired spacing. The slots being inclined from the post and the extremity 17 extending above the top line, the wires are not easily displaced and will remain in position until all are properly seated, 25 when the keeper may be inserted and the several wires locked in place.

It will be seen that the several wires, by reason of the large number of slots, may be differently spaced, as desired, and that after 30 the fence has been built the spacing may be changed and wires removed or added, as conditions may make desirable. In like manner the wires may be all removed and reeled and used again, as the wire and its coating have 35 not been broken by driving staples and the like. It is also obvious that, owing to the small intervals between the several slots, the fastener may with equally satisfactory results be used to secure a wire fabric or a fabric 40 may be used below and wires above.

Having thus described the invention, what is claimed is—

1. A wire-fastening attachment for posts and the like comprising a plate and tongues 45 integral with one edge of and extending at an angle to the plate, the ends of said tongues being curled and the curls disposed at angles to and projecting above the tongues.

2. A wire-fastening attachment for posts 50 and the like comprising a plate, obliquely-disposed spaced tongues integral with, and

extending at an angle from one edge of the plate, and obliquely-disposed curls at the ends of the tongues and projecting thereabove to form retainers.

- 5 3. A wire-fastening attachment for posts and the like comprising a plate, obliquely-disposed tongues extending therefrom and spaced apart, and curls disposed obliquely at the ends of the tongues and spaced from the plate, the openings in said curls alining.
4. A wire-fastening attachment for posts and the like comprising a plate, obliquely-disposed tongues extending therefrom and spaced apart, and curls disposed obliquely at
- 15 the ends of the tongues and spaced from the plate, the openings in said curls alining, and a keeper removably mounted within the curls.
5. A wire-fastening attachment for posts and the like comprising a plate, obliquely-disposed tongues extending therefrom and spaced apart, and curls disposed obliquely at
- 20

the ends of the tongues and spaced from the plate, the openings in said curls alining, and said curls extending above the tongues to constitute retainers.

6. A wire-fastening attachment for posts and the like comprising a plate, obliquely-disposed tongues extending therefrom and spaced apart, and curls disposed obliquely at the ends of the tongues and spaced from the plate, openings in said curls alining, and said curls extending above the tongues to constitute retainers and a keeper removably mounted within the curls.

In testimony that I claim the foregoing as 35 my own I have hereto affixed my signature in the presence of two witnesses.

CHARLES WAID ROUSH.
